DESIGN FOR A VACUUM CLEANER NOZZLE

Gustaf Einar Lofgren, Riverside, Conn., assignor
to Electrolux Corporation, Dover, Del., a cor-
poration of Delaware

Application April 14, 1936, Serial No. 62,119

Term of patent 14 years

To all whom it may concern:

Be it known that I, Gustaf Einar Lofgren, a subject of the King of Sweden, residing in Riverside, Connecticut, have invented a new, original, and ornamental Design for a Vacuum Cleaner Nozzle, of which the following is a specification, reference being had to the accompanying drawing, forming part thereof:—

Fig. 1 is a perspective view of a vacuum cleaner

nozzle showing my new design as seen from the front and above; and

Fig. 2 is a perspective view of the vacuum cleaner nozzle shown in Fig. 1 as seen from the rear and above.

I claim:

The ornamental design for a vacuum cleaner nozzle, as shown.

GUSTAF EINAR LOFGREN.
